HEEL-ATTACHING MACHINE

Francis L. Brandt, Marblehead, Mass., assignor to
United Shoe Machinery Corporation, Paterson,
N. J., a corporation of New Jersey

Application August 10, 1937, Serial No. 158,415

19 Claims. (Cl. 1—32)

My invention relates to heel-attaching machines or to those for attaching heel-portions, it being particularly concerned with apparatus arranged for manual actuation and adapted for use by repair men.

The invention has as an object the provision of a machine which is simple, inexpensive and convenient to operate. In the attainment of this object, the following features are improved: the manner of arranging and actuating the work-support, especially with reference to the yieldable mounting and retention upon a plunger, which may furnish the body of the support, of a top-portion, which constitutes the work-support proper; the means for retaining the plunger in any position to which it may be moved by the operator, this facilitating the making of adjustments in the heel-pressure mechanism co-operating with the support; the driver-assembly, particularly as to the manner of giving access to it and the securing of drivers with inclined fastening-engaging ends upon their plunger in predetermined angular positions about their axes; and the adjusting means for the work-pressure mechanism, both as to the abutment for the tread-surface of a heel and as to the rear abutment.

One of the several embodiments which my invention may assume is illustrated in the accompanying drawings, in which

Fig. 1 is a side elevation of my improved heel-attaching machine, with portions in section;

Fig. 2, a sectional elevation of the elements more closely associated with the work, these being in a different position from that appearing in Fig. 1; and

Fig. 3, an enlarged horizontal section on the line III—III of Fig. 1.

The character 10 designates a frame, which is herein shown as of the type arranged to have its base secured to a bench and having an overhang arm 12 curved rearwardly and then forwardly above the base. Mounted to move vertically through an opening in the base is a plunger 14 furnishing the body-portion of a work-support or jack. To receive its movement, the plunger is provided at its forward side with a rack 16, with which meshes a pinion 18 fast upon a short horizontal shaft 19 journaled across the base. Secured to the shaft is a hand-lever 20 rising at one side of the frame-arm, arranged to be grasped by the operator and swung in opposite directions to either raise or lower the plunger. To yieldably maintain the plunger at the point to which it may be moved by the operator, there acts upon it a friction device, shown as comprising

ing a plug 21 sliding in a horizontal bore in the frame. The plug is forced against the plunger by a spring 22 backed by a screw 23 threaded into the outer end of the bore. Guided for vertical movement about the plunger is an upper portion 24 which furnishes the work-support proper. This conforms generally to the counter-portion of a shoe, such as is shown at S, the insole thereof resting upon the upper surface of the member, positioned for the attaching operation. From the member 24 depends a sleeve-portion 26, which surrounds and is guided by the outside of the plunger. The support-top 24 is held normally raised by a helical spring 28 contained in a longitudinal passage 30 in the plunger. At its lower extremity, the spring abuts against the plunger, while at its upper end, it contacts with a sleeve 32 movable freely in the passage. The expansion of the spring and the extent to which the sleeve may be elevated are limited by contact of the latter with a head 34 formed on the upper extremity of a rod 36 which passes through them and is threaded into the plunger at the bottom of the passage 30. The head 34 is slotted to receive a screw-driver, so the rod may be inserted and removed, and the parts readily assembled and disassembled. The rod and sleeve extend into a cylindrical recess 38 within the sleeve-portion 26, the top wall of the recess resting upon the upper end of the sleeve 32, with the rod-head 34 in a central passage 40 in the support-top 24. The spring 28, through the sleeve 32, thus supports the top 24 to yield under pressure.

About the passage 40 in the top are driver-passages 42, herein shown as five in number. These correspond in arrangement to the particular design in accordance with which nails N or other attaching fastenings are to be inserted in the work. With their lower ends resting upon the upper extremity of the plunger 14 and passing through the recess 38 into the passages 42 are drivers 44, one for each of said passages. The drivers are accurately positioned upon the plunger in vertical alinement with the passages by a locating plate 46, carried on the plunger and containing a set of five openings 48 into which the driver-ends fit. Preferably, the drivers have nail-engaging ends 50 which are downwardly and inwardly inclined to hold the nails with their entering points toward the inner sides of the passages 42, so when driven, said nails will toe in. This reduces the liability of emergence of the points through the side-wall of a heel H being attached. To insure the correct relation of these inclined ends about the axes of the drivers and

to hold them against separation from the plunger, each driver has at its side just above the plate 46, a slot 52, each slot being in a definite angular relation about the axis of the driver to the inclination of the driver-end. Resting upon the plate 46 is a polygonal plate 54 having an opening 55 to receive the sleeve 32, the plate being of such width that it will occupy the slots 52, as these are located just above the upper surface of the plate 46. The plate 54 has a side 56 corresponding to each driver, the angle between the sides being such that as the edges of the plates lie in the slots, they will so limit the rotation of the drivers about their axes in the openings 48 of the plate 46 that the inclined ends 50 will be correctly positioned. To secure the two plates on the plunger, there passes through registering openings in them the shank of a screw 58. This screw is threaded into the top of the plunger 14 and holds the plates and the drivers in the desired relation, also securing them to the plunger. An elongated cylindrical head 59 of the screw extends into a passage 60 in the top 24, so the screw is made accessible when the top is in place, and at the same time said top is held against rotation upon the plunger to maintain the alignment of the drivers with the passages 42. In Fig. 3 of the drawings, clearance-spaces will be seen between the edges of the plate 54 and the inner walls of the slots 52 and also about the sleeve 32 in the opening 55. In assembling the drivers 44 upon their plunger, with the top 24 removed, the ends of the four front drivers are placed in the plate-openings 48 and the plate 54 slipped from the rear over the surface of the plate 46 until its edges enter the driver-slots 52. The clearance-spaces in the slots 52 and the opening 55 are sufficient to permit the plate 54 to be thus moved until the rear driver may be inserted in its opening 48. Then, the plate 54 is shifted rearwardly into the slot in this rear driver, and the openings in the two plates and in the plunger are brought into registration. This allows the screw 58 to be inserted to secure these elements together. Thereupon, the top 24 may be placed upon the plunger, with the drivers in the passages 42 and the rod-head 34 and the screw-head 59 in the respective passages 40 and 60.

A heel may be positioned on the heel-seat of a shoe carried by the top 24 for the operations upon it and the nail-inserting pressure resisted by tread and rear abutments. Threaded vertically through the overhanging arm 12 is a screw 62 having fast upon its upper extremity a hand-wheel 64 and at its lower extremity a reduced portion 66 surrounded by a carrier-block 68. The carrier is held against displacement from the screw 62 by a retaining screw 70, the end of which enters a circumferential groove in the portion 66. To hold the carrier against rotation as the screw 62 turns, a rod 72 rises from its rear and passes freely through an opening in the arm 12. Projecting from the front of the carrier is a lug 74, through which is threaded vertically a contact-screw 76 provided at its upper end with a finger-piece 78 convenient for manipulation by the operator. Pivoted at 80 upon the carrier is an abutment-plate 82, the outer portion of which is urged against the screw 76 by a torsion-spring 84 encircling the pivot-pin 80 and having its ends engaging, respectively, the carrier and plate. The spring holds the plate constantly against the screw, so it follows the latter, as it is adjusted to give the proper angles to the tread-surface of the plate for heels of different pitches.

Between the ends of the frame-arm 12 is a forwardly and downwardly inclined passage 86, in which is free to move longitudinally a screw 88. A tension-spring 90 joining the screw to the frame at the outer end of the passage holds against said frame a nut 92 upon the screw. A screw 94 threaded through the frame into a longitudinal slot 96 in the screw 88 retains the latter screw against rotation while it is being adjusted by the nut 92. Attached to the forward extremity of the screw 88 by a bolt 98 is a transversely curved, padded rear abutment 100 against which a heel to be attached may rest. As the nut 92 is rotated, the spring keeps it against the frame, and the abutment may be moved over the work-support to a greater or less distance to correctly position a heel upon the heel-seat of a supported shoe.

There may be applied to the plunger 14 a shoe-supporting top and a driver-assembly, furnishing the nailing design most suitable for the work to be performed. The operator supplies a load of nails N to the passages 42, their heads being supported upon the inclined ends 50 of the drivers with the points resting against the inner sides of the passages. These points will be initially a substantial distance below the upper surfaces of the top 24. With the plunger 14 lowered, the plate 82 and abutment 100 are so located by the handwheel 64 and nut 92, respectively, that a shoe S may be applied to the support, and a heel H placed upon its heel-seat. The work may thus be introduced into the machine. The operator draws forward the lever 20, until the surfaces at the tread and rear of the heel, with which the abutments 82 and 100 contact, are close to these. He may then release the lever, the work-support being retained in the position to which it is moved by the friction device 21. This leaves both hands of the operator free to position the work and adjust the abutments by turning the screw 76 and the nut 92 until engagement is obtained which will hold the heel against slipping upon the heel-seat during the inserting operation. Thereupon, further forward movement of the lever first brings the work against the abutment. This causes the spring 28 to yield, and as the nails are being raised by the drivers through the spaces which exist between their points and the insole, the top 24 is being forced against said insole, this clamping the work by the force created by the compressed spring. When the nail-points reach the insole and are driven through it into the heel in an inwardly inclined direction, upon continued depression of the lever, the attachment of the heel to the shoe is completed. Elevation of the lever lowers the support to release the work for its removal.

Having described my invention, what I claim as new and desire to secure by Letters Patent of the United States is:

1. In combination, a work-support comprising a body-portion and a top-portion movable thereon and provided with passages, drivers mounted upon the body-portion and movable in the passages, a spring interposed between the support-ports, and a retaining member carried by the body-portion and limiting the movement of the top-portion under the influence of the spring while leaving said top-portion free for separation from the body-portion.
2. In a heel-attaching machine, a work-support comprising a body-portion and a top-portion movable thereon and provided with passages, drivers secured to the end of the body-portion and movable in the passages, a spring interposed between the support-ports, and a rod se-

- cured to and extending through the body-portion into the top-portion and there having means to limit the movement of said top-portion under the influence of the spring.
- 5 3. In a heel-attaching machine, a work-support comprising a body-portion and a top-portion movable thereon and provided with passages, drivers secured to the end of the body-portion and movable in the passages, a spring interposed between the support-portions, a rod secured to and extending through the body-portion into the top-portion and having a head, and a spring surrounding the rod between the body-portion and the head.
- 10 4. In combination, a work-support comprising a body-portion and a top-portion movable thereon and provided with passages, drivers mounted upon the body-portion and movable in the passages, a rod extending through the body-portion into the top-portion and having a head to limit the movement of said top-portion, a sleeve surrounding the rod and contacting with the head, and a spring surrounding the rod and contacting with the sleeve and body-portion.
- 15 5. In a heel-attaching machine, the combination with a heel-abutment, of a plunger movable toward and from the abutment and having a longitudinal passage, a shoe-support movable upon the plunger and provided with driver-passages, drivers mounted upon the plunger and operating in their passages in the support, a support-retaining rod extending through the plunger-passage and being threaded into the plunger, and a spring surrounding the rod in the plunger-passage and exerting its force to elevate the shoe-support.
- 20 6. In a heel-attaching machine, the combination with a heel-abutment, of a plunger movable toward and from the abutment and having a longitudinal passage, a shoe-support movable upon the plunger and provided with driver-passages, drivers mounted upon the plunger and operating in their passages in the support, a headed rod extending through the plunger-passage and being threaded into the plunger, a sleeve surrounding the rod beneath the head and upon which the shoe-support rests, and a spring surrounding the rod and interposed between the plunger and sleeve.
- 25 7. In a heel-attaching machine, the combination with a heel-abutment, of a plunger movable toward and from the abutment and having a longitudinal passage, a shoe-support movable upon the plunger and provided with driver-passages and with a central passage, drivers mounted upon the plunger and operating in their passages in the support, a rod having a head in which is a slot, said rod extending through the plunger-passage and being threaded into the plunger with its head in the central passage of the support, a sleeve surrounding the rod beneath the head and upon which the shoe-support rests, and a spring surrounding the rod and interposed between the plunger and sleeve.
- 30 8. In combination, a heel-abutment, a plunger movable toward and from the abutment and having mounted upon it a shoe-support provided with driver-passages and drivers movable in the passages, means whereby the operator may actuate the plunger, and means arranged to retain the plunger in the position to which it is moved by the operator.
- 35 9. In a heel-attaching machine, a frame, a heel-abutment carried by the frame, a plunger movable in the frame toward and from the abutment

and having mounted upon it a shoe-support provided with driver-passages and drivers movable in the passages, means whereby the operator may actuate the plunger, and a friction device movable upon the frame and contacting with the plunger.

10. In combination, a driver-plunger, a plurality of fastening-drivers carried by the plunger and each having a fastening-engaging end inclined with respect to the axis of the driver and being provided at its side with a slot having a definite angular relation to the inclined end about the axis of the driver, and a polygonal plate secured to the plunger and having a peripheral portion corresponding to each driver and arranged to enter its slot.

15 11. In a heel-attaching machine, a driver-plunger, a plurality of fastening-drivers carried by the plunger and each having a fastening-engaging end inclined with respect to the axis of the driver and being provided at its side with a slot having a definite angular relation to the inclined end about the axis of the driver, a polygonal plate having a peripheral portion corresponding to each driver and arranged to enter its slot, there being clearance between the drivers of a group thereof and the corresponding plate-edges sufficient to allow the plate to be moved to one side for the application to the plunger of another driver, and a screw by which the plate may be secured to the plunger to lock all the drivers in position.

20 12. In combination, a work-support provided with driver-passages and with an opening, a plunger cooperating with the support and having drivers movable in the passages, a plate arranged to position the drivers upon the plunger, and a member securing the plate to the plunger and extending into the support-opening.

25 13. In combination, a plunger, a plurality of fastening-drivers carried by the plunger, a plate having openings to receive the drivers, a plate engaging the drivers to determine their angular positions about their axes, and means for securing both plates to the plunger.

30 14. In a heel-attaching machine, a plunger, a plurality of fastening-drivers carried by the plunger, a locating plate having openings to receive the drivers, a plate engaging the drivers to determine their angular positions about their axes and to retain them in the openings of the locating plate, and means for securing both plates to the plunger.

35 15. In a heel-attaching machine, a plunger, a plurality of fastening-drivers having their ends resting against the end of the plunger, a plate contacting with the end of the plunger and having openings in which the drivers fit, a plate resting against that having the openings and provided with an edge-portion for engagement with each driver, and a screw securing both plates to the plunger.

40 16. In a heel-attaching machine, a driver-plunger, a plurality of fastening-drivers having their ends resting against the end of the plunger, each driver being provided in its side with a slot, a plate contacting with the end of the plunger and having openings in which the drivers fit, a polygonal plate resting against that having the openings and provided with an edge-portion arranged to enter the slot of each driver, and a screw securing both plates to the plunger.

45 17. In combination, a frame in which is an opening, a work-support mounted upon the frame, a screw rotatable in the frame to move toward and from the work-support and provided with a reduced end in which is a circumferential groove,

- 5 a carrier into which the reduced end of the screw projects, a rod extending from the carrier into the frame-opening, a screw threaded through the carrier and entering the groove, and a heel-pressure-abutment pivoted upon the carrier for co-operation with the support.
- 10 18. In a heel-attaching machine, a frame in which is an opening, a work-support mounted upon the frame, a screw rotatable in the frame to move toward and from the work-support and provided with a reduced end in which is a circumferential groove, a carrier into which the reduced end of the screw projects, the carrier having a forwardly extending lug, a screw threaded through the lug with its head above said lug, a rod extending from the carrier into the frame-opening, a screw threaded through the carrier and

entering the groove, a heel-pressure-abutment pivoted upon the carrier for co-operation with the support, and a torsion-spring surrounding the pivot of the abutment and acting upon the carrier to urge it against the lower end of the screw in 5 the lug.

19. In combination, a frame in which is a passage, a work-support mounted upon the frame, a heel-tread-abutment movable upon the frame toward and from the support, a screw movable in the frame-passage and carrying a nut, there being means for preventing the screw from rotating in the frame, a spring connecting the screw and frame to draw the nut against said frame, and a rear abutment carried by the end of the screw in 15 co-operation with the tread-abutment.

FRANCIS L. BRANDT.
